United States Patent Office.

WILLIAM WEAVER, OF NASHUA, NEW HAMPSHIRE.

Letters Patent No. 70,657, dated November 5, 1867.

IMPROVED COMBINATION BENCH.

The Schedule referred to in these Letters Patent and making part of the same.

TO ALL WHOM IT MAY CONCERN:

Be it known that I, WILLIAM WEAVER, of Nashua, in the county of Hillsborough, and State of New Hampshire, have invented certain new and useful Improvements in the Benches which are used by workers of marble or other stone, of which the following is a full, clear, and exact description, reference being had to the accompanying drawings, making part of this specification, in which—

Figure 1, sheet 1, is a longitudinal vertical section of my improved combination bench, and shows the boring apparatus in the act of boring the dowel-hole in the base I of a head-stone.

Figure 2, sheet 1, is a front elevation showing a head-stone, H, in an inverted position to have the bottom end of the stone squared and finished.

Figure 3, sheet 1, is a front elevation showing the head-stone in a position to have the edge chamfered or moulded.

Figure 4, sheet 1, is an end elevation of fig. 3.

Figure 5, sheet 2, is a plan or top view of fig. 2, sheet 1.

Figure 6, sheet 2, is a rear side elevation, with a stone, H, in position for lettering or carving.

Figure 7 is a front elevation, with a head-stone in position for working a gothic head or top end.

Figure 8 is a front elevation, with a base of a head-stone in position for chamfering or cornering the end.

Figure 9, sheet 2, is a top view after the upper and transverse sliding portion has been removed.

In my said invention, the top portion A.A of the bench is stationary, being fastened to the transverse sliding pieces B B, but the middle portion C of the top is movable, and made in pieces of different widths, and placed longitudinally on the top of the pieces B between the stationary pieces A. The movable pieces may be slid out endways, as shown in fig. 2, and an inverted head-stone placed between two of the pieces, and keyed in so as to hold the stone while the bottom end is squared and finished. The screw a, passing through the rear top piece A, fig. 5, is screwed up to hold the pieces C firmly in the place desired. A block, D, shown in figs. 1 and 2, beneath the top, keeps the inner ends of the movable pieces up, when slid out, as shown in fig. 5. A movable and adjustable step, E, shown in figs. 2, 5, 7, and 9, is arranged on the front legs of the bench, to hold a head-stone for finishing the edges, the same being shown in red (dotted) lines in fig. 2. This step may be raised or lowered by the use of dowels connected therewith, and entering holes e in the edges of the front posts, thereby providing for a wider or narrower stone. Two transverse movable rising skids F are employed between the sliding pieces B and the bed-plate G, to raise the movable top to different heights and accommodate different-sized stones, and in different positions, and when the movable top is so raised, the block D, which is made of the thickness, width, and length to correspond with different heights of the top, supports the end of the stone nearest the centre of the bench, as for drilling the dowel-holes, as shown in fig. 1. In chamfering or moulding the edge of a stone, it is designed to remove the central top portion of the bench, and use the movable pieces C for blocking up the stone, as shown in figs. 3 and 4. In lettering or carving a thin flat stone, it is necessary to invert the sliding top portion of the bench, and place it on the top of the posts, as shown in fig. 6, in which case the stone H is placed on the top of the inverted pieces B, and pins or bolts h are inserted through the pieces A into the tops of the back posts L, to hold the parts from sliding or being moved. In working off a gothic head to a stone, one of the top pieces C is removed, and the stone set in between other two pieces, and keyed or otherwise secured in the position shown in fig. 7. In chamfering the end of a base or elongated block of stone, it is placed in a position shown in fig. 8, and, if a short piece, the block D, or any other suitable block, is placed between the lower end of the stone and the side piece B. When a large but narrow stone is to be finished on the edge, it is keyed into an edging notch, e, formed in the overhanging end of the bed-plate G, (as shown in fig. 9.) The screw g (shown in fig. 3) passes through the front post O, to hold the top portion in position transversely. The boring apparatus used in my improved bench, consists of a longitudinal shaft, d, and a vertical shaft, h, driven by a crank, f, and connected by bevel gears n. The gear on the vertical shaft is loose enough to allow the shaft to slide freely up or down, but is held in rotary action with the shaft d by a key or feather, x, secured to the shaft, and working in a groove or key-way at one side of the hole through the gear. The lower end of the vertical shaft is seated in a step near one end of a foot-lever, m, to the outer end p of which downward pressure is applied when turning the crank f, thus forcing the drill g upwards into the stone I.

Other positions than those above shown, for placing and holding the different sizes and forms of stone to be worked, will be readily suggested to the skillful mechanic who may use my improved bench.

What I claim as new, and desire to secure by Letters Patent, is—

1. The fixed and movable portions A and C of the top, when arranged for adjustment substantially in the manner and for the purposes set forth.
2. The movable sliding upper portion of the bench, composed of the fixed and movable top and transverse sliding pieces B B, when arranged substantially as and for the purpose specified.
3. The movable and adjustable rising skids F, arranged in the manner and for the purpose specified.
4. The drilling mechanism, constructed as shown and described, combined with a bench, substantially in the manner and for the purpose set forth.
5. The movable and reversible block D, constructed in the manner and for the purposes specified.
6. The movable and adjustable step E, arranged for operation substantially in the manner and for the purpose set forth.
7. The employment of the adjusting-screws α and g , or the equivalent thereof, substantially in the manner and for separate purposes as set forth.
8. The edging notch e in the end of the portion G of the bench, for the purpose specified.
9. The combination of the movable sliding upper portion, as described, the skids F, block D, step E, screws α and g , or the equivalent, with or without the drilling mechanism, the whole constructed and arranged for adjustment and operation substantially as and for the purposes set forth.

WILLIAM WEAVER.
